EXPANSIBLE JEWELRY CLASP.

Alfred Philippe, Scarsdale, N. Y., assignor to Tri-fari, Krussman and Fishel, Inc., a corporation of New York

Application July 14, 1950, Serial No. 173,755

1 Claim. (Cl. 267—71)

1

This invention relates to expandible jewelry clasps which, though of more general application, are especially designed for use on ladies' necklaces, particularly those known as chokers or collars.

As conducive to a clear understanding of the invention, it is noted that ladies' necklaces of the above type are to fit snugly but comfortably about the neck of the wearer and not slip toward the base of the neck and unless such snug fit is achieved, the desired effect of the jewelry collar is lost.

If to achieve such snug fit, the collar is custom-made, it will be relatively expensive and where a large stock of collars of different sizes are kept on hand to fit the purchaser, the cost of such stock may be prohibitive, especially to the small retailer.

Even if a collar should be purchased that snugly fits the neck, if there is no extensibility afforded in the length of the collar, it would be difficult for the wearer to breathe or swallow and such collar would be extremely uncomfortable.

It is accordingly among the objects of the invention to provide an expandible clasp which may readily be incorporated in a jewelry collar, and which clasp when fastened to retain such collar about the neck of the wearer, will snugly hold such collar in place, yet will automatically adjust its length to compensate for slight departure of the neck circumferences from the size of the collar and also to compensate for variations in neck circumferences caused by breathing and swallowing, which clasp is light in weight, relatively small in size, dependable in action and has but few relatively inexpensive parts that may readily be assembled and are not likely to become deranged.

In the accompanying drawings in which are shown one or more of various possible embodiments of the several features of the invention,

Fig. 1 is a fragmentary plan view of a jewelry collar incorporating one embodiment of the clasp,

Fig. 2 is a plan view on a larger scale, partly in cross section with parts broken away, of one of the fastener elements of the clasp shown in Fig. 1,

Fig. 3 is a longitudinal sectional view taken along line 3—3 of Fig. 2,

Fig. 4 is a transverse sectional view taken along line 4—4 of Fig. 2,

Fig. 5 is a perspective, exploded view of one of the fastener elements,

Fig. 6 is a view similar to Fig. 2 of another embodiment of the clasp,

2

Fig. 7 is a longitudinal sectional view taken along line 7—7 of Fig. 6,

Fig. 8 is a transverse sectional view taken along line 8—8 of Fig. 6 and,

Fig. 9 is an exploded perspective view of the fastener element of Figs. 6 to 8 inclusive.

Referring now to the drawings, in Fig. 1 is shown one embodiment of the clasp 11, incorporated in a jewelry collar 12 of the type illustratively having a plurality of parallel strands 13.

The clasp 11 desirably has two identical fastener elements 14 and 15 which may be connected together by a conventional hooking link 16.

As shown in Figs. 2 to 5 inclusive, the fastener element 15 desirably comprises a casing 21, which, though it could be made in any suitable manner, desirably comprises a substantially U-shaped base piece 22 preferably a unitary stamping, having parallel side legs 23 and 24 and a cross piece 25 joining adjacent ends of said legs, said cross piece desirably having an upstanding flange 26 along the inner edge thereof between legs 23 and 24.

The outer edges and the free ends of legs 23 and 24 desirably have upstanding walls 27 and 28 respectively preferably formed integral therewith and the cross piece 25 desirably has a pair of rearwardly extending tongues 29, longitudinally aligned, respectively with said legs 23 and 24.

Positioned on the upper edges of walls 27 and 28 and affixed thereon as by welding or soldering is a substantially U-shaped cover member 31 which may carry suitable decorations such as diamonds, rhinestones or the like thereon and which desirably has a transverse connector bar 32 across the legs 33 and 34 thereof adjacent the free ends of legs 23 and 24, the bar 32 of one of said fastener elements serving as the pivot for the hooking link 16 which may engage the bar 32 on the other of said fastener elements to retain the two fastener elements 14 and 15 together.

With the cover member 31 mounted on the base piece 22, a channel will be defined longitudinally of each of said legs 23 and 24 in which a slide member 37 may be positioned through the slot 40 in the end of the casing.

As shown in Fig. 5, the slide member 37 is also desirably substantially U-shaped, having parallel legs 38 and 39 and a cross piece 41 connecting the end of said legs and preferably formed integral therewith. Each of the longitudinal edges of said legs as well as each of the free ends thereof has a depending wall 42 and 43 respectively which define a longitudinal pocket on each of said legs 38 and 39.

55 In assembling the clasp 11, it is merely neces-

sary to position the legs 38 and 39 of slide member 37 in the associated channels in the casing 21 as shown in Figs. 2 to 5 inclusive. A coil spring 44 is then positioned in each of the pockets between the side walls 42 of legs 38 and 39 and retained therein by bending upwardly the tongues 29 which will extend respectively into each of said pockets.

The coil springs are of such length that they will be only slightly compressed between the 10 associated tongues 29 rigid with the housing and the end walls 43 of the pockets of the slide member 37 and will normally urge said slide member into the casing.

The assembly of the collar shown in Figs. 1 to 5 may then be completed by fastening the ends of 15 each of the strands 13 to the eyes 45 formed on the cross piece 41 of the slide members 37.

In the embodiment of the clasp shown in Figs. 6 to 9 inclusive which is especially designed for use with a single-strand necklace, the clasp also desirably has two fastener elements 51 and 52 which also are identical.

As shown in Figs. 7 and 9, the fastener element 51 desirably comprises a casing 53 which may have a substantially rectangular base piece 54 having upstanding walls 55 along the longitudinal edges and 56 along one of the ends thereof, the other end of said base piece 54 having a tongue 57 projecting rearwardly midway between its sides. The base piece also desirably has a substantially rectangular opening 59 midway between side walls 55 with an upstanding tongue 58 on the inner edge of said opening. End wall 56 serves to hold a conventional hooking link 61 which, as shown in Fig. 7, extends through opening 59.

Positioned on the upper edges of walls 55 and 56 and affixed thereon as by welding or soldering is a cover member 63 which, as shown in Fig. 8, has spaced longitudinal ribs 64 on the undersurface thereof forming shoulders 60 along the outer edges thereof which rest on said upper edges and defining a longitudinal groove 65 therebetween. As shown in Fig. 8 the undersurfaces of the ribs are slightly spaced from the base piece 54 defining a pair of spaced parallel passageways 67. The cover member 63 desirably has a substantially rectangular cut out 66 at one end thereof which may be aligned with the opening 59 in base piece 54 to permit insertion of the hooking link 61.

With the cover member 63 affixed upon the base piece 54, the groove 65 and the longitudinal passageways 67 will provide a channel in which a slide member 68 may be positioned.

The slide member 68 is desirably substantially rectangular in shape having a longitudinal median depression 69 in the underface thereof with laterally extending wings 71, said depression having a wall 72 at one end thereof and defining a pocket in which a coil spring 73 may be positioned.

In assembling the clasp shown in Figs. 6 to 9 inclusive, it is merely necessary to position the slide member 68 in the casing 53 with the wings 71 in the associated passageways 67 and with the depression 69 in the groove 65. The coil spring 73 is then positioned in the pocket formed by groove 65 and is retained therein by bending 70 upwardly the tongue 57 which will extend into said pocket.

As the coil spring 73 will be but slightly compressed between tongue 57 rigid with the housing and end wall 72 of the slide member 68, the lat-

ter will normally be urged into the casing, its inward movement being restrained by tongue 58 which functions as a stop.

The assembly of the single strand collar may then be completed by fastening the ends of the strand to the eyes 75 formed in the outer end of slide member 68.

In the embodiment of the clasp shown in Figs. 1 to 5 inclusive, each of the coil springs 44 will be contained in a closed chamber defined by the side walls 42 and end walls 43 of slide member 37 and legs 23 and 24 and tongues 29 of the casing.

Similarly in the embodiment of the clasp shown in Figs. 6 to 9 inclusive, the spring 73 will also be contained in a closed chamber defined by the depression 69 and end wall 72 of the slide member 75 and by the base piece 54 and tongue 57 of the casing.

In both embodiments herein shown, the associated chamber will vary in size depending upon the position of the slide member with respect to the casing and the coil springs will be securely retained in place without likelihood of dislodgment and as the springs are enclosed regardless of the position of the slide members they are not likely to collect dirt or to catch on the skin of the wearer with resultant discomfort to the latter.

In using a collar having a clasp constructed according to either of the embodiments herein described the wearer need merely position such collar around her neck and connect the two fastener elements together by means of the conventional link.

If the unexpanded length of the encompassing collar should be slightly less than required for a snug yet comfortable fit, the slide member will move out of the casing against the resistance of the coil springs and automatically adjust the collar length to the proper size. Thus the collar will be retained around the neck without sliding from the desired position thereon.

By reason of the expandable nature of the clasp, the wearer may swallow and breathe without feeling any constriction, as the slide member will move in and out of the casing to compensate for slight variations in neck circumference.

With the expandable clasp construction above described, it is only necessary to have a stock of collars on hand sized approximately every half inch, which considerably reduces the number of collars that would otherwise be required to fit every wearer, and as the clasp constructed according to the present invention may be relatively small in size, when attached to a collar, it will not detract from the desired overall appearance of the article.

As many changes could be made in the above construction, and many apparently widely different embodiments of this invention could be made without departing from the scope of the claim, it is intended that all matter contained in the above description or shown in the accompanying drawings shall be interpreted as illustrative and not in a limiting sense.

Having thus described my invention, what I claim as new and desire to secure by Letters Patent of the United States is:

An expandible clasp comprising a casing having a base piece and a cover piece affixed at their lateral edges, said cover piece having spaced parallel longitudinal ribs defining a groove therebetween with the undersurface of said ribs being spaced from said base piece defining a longitudinal passageway on each side of said groove,

said passageways and said groove defining a channel, a tongue rigid with said base piece and extending upwardly into said groove at the outer end thereof, a slide member in said channel, said slide member having a longitudinal median depression with a wall at the inner end thereof and open at the outer end thereof, and having lateral wings on each side of said depression, said depression being positioned in said groove and said wings in the respective passageways, a coil spring in said depression, said spring normally being slightly compressed between the end wall of said

depression and said tongue thereby urging said slide member into said casing.

ALFRED PHILIPPE.
